UNITED STATES PATENT OFFICE.

JONAS BROLIN, OF SIOUX FALLS, SOUTH DAKOTA.

PROCESS OF REMOVING FIBER FROM UNRETTED FLAX-STRAW AND PREPARING THE RESIDUE FOR STOCK FOOD.

1,239,667.

Specification of Letters Patent. Patented Sept. 11, 1917.

Application filed April 1, 1916. Serial No. 88,245.

To all whom it may concern:

Be it known that I, JONAS BROLIN, a citizen of the United States, residing at Sioux Falls, in the county of Minnehaha and State 5 of South Dakota, have invented certain new and useful Improvements in Processes of Removing Fiber from Unretted Flax-Straw and Preparing the Residue for Stock Food, of which the following is a specification.

10 My invention relates to the process of separating the food portions of unretted flax straw from the fibers and of preparing said separated food portions for use as a stock food.

15 It is the object of my invention to subject flax straw in its unretted or naturally cured condition as the same comes from an ordinary flaxseed threshing machine to a continuous set of operations whereby the cortex 20 and other non-fibrous portions of the flax straw are removed therefrom and separated from the fibers. The fibers secured by this process are gathered together and formed into bales for further treatment at the fiber 25 mills in the usual way. The shives or non-fibrous portions of the straw, which have a high nutritive value as food for stock, are not only effectively removed and entirely separated from the fibers, which are indi-

30 gestible and injurious in a stock food, but in connection with the process of fiber removal and as a direct continuation thereof such food material is additionally treated so as to render the same immediately available 35 as a stock food.

Flax straw where the same has been properly cut and cured at the ripening of the flaxseed and where, after threshing the straw has not been permitted to rot, pos- 40 sesses a very high food content for domestic animals such as cattle, hogs, etc. This food is not, however, available in the natural state of the straw because of the presence of the large amount of flax fiber and 45 its tough and indigestible character. This fiber must be removed before the food becomes available, and the fiber itself, as is well-known, is valuable in the textile and twine making industries. Ordinarily, the 50 separation of the fiber from the other portions of the flax straw has been for the purpose of securing the fiber only, and the methods employed have not been conducive to the use of the shive for stock feeding 55 purposes. This material as it usually comes

from the decorticating mechanism is not only unfit for feeding purposes in its original condition, but if left untreated or stored rapidly deteriorates, becoming musty and diseased, so that any use of it for a stock 60 food is soon impossible. This is because the flax straw in its natural state is infested with numerous fungi and parasites. The fine shive after decortication quickly absorbs moisture and the fungi and parasites 65 rapidly multiply and cause chemical reactions which soon destroy the food values of the product. By immediately cleaning the shive and mixing it at once with some material such as crude molasses, which destroys 70 and prevents growth of fungi and parasites, a high grade stock food may be produced during the same set of operations which removes the fiber from the flax straw.

The full objects and advantages of my invention will appear in connection with the detailed description thereof and are particularly pointed out in the claims.

In the drawings, illustrating the application of my invention in one form,

Figure 1 is a flow sheet showing the machines acting upon the stock and the courses of the stock throughout the process. Fig. 2 is a diagrammatic plan view of a number of the machines and conveyors in their relative positions. Fig. 3 is a view similar to Fig. 2 of the remainder of the system. Fig. 4 is a diagrammatic sectional elevational view taken on line 4-4 of Fig. 2. Fig. 5 is a view similar to Fig. 4 taken on line 5-5 90 of Fig. 3.

The location and operation of the machines and instruments of conveyance used in my process for forming stock food from flax straw is best shown in Figs. 2, 3, 4 95 and 5. The flax straw as it is received at the mill may be either baled or loose. Any baled straw is first fed into a suitable bale breaking or opening machine 10 which comprises a toothed roll 11, a corrugated roll 12 and 100 a short belt conveyor 13. As the baled straw passes through this machine it is loosened and torn apart so that when it leaves the machine it is in a condition similar to that of the ordinary or unbaled stock. Beneath the outlet of the bale breaker 10 is positioned a horizontal belt conveyor 14 which discharges the loosened straw to a hopper 15 immediately in front of decorticating ma- 105 chinery to be presently described. At right 110

angles to the short conveyer 14 is a long belt conveyer 16 which is adapted to discharge on said first-named belt. All of the loose straw is pitched or placed on this belt and 5 is hence discharged on the belt 14 together with the stock from the bale-breaker 10. By this means both baled and loose straw is delivered to the receiving hopper 15 in the proper form to be acted upon by the decorti-
10 cating machinery.

In close proximity to hopper 15 is situated a straw feeder 17 comprising a toothed drum 18, a pair of rolls 19 and 20 and a concave screen 21. This feeder picks up the straw 15 from the hopper 15, passing it between rolls 19 and 20 and the drum 18, and feeds it downwardly into a series of break rolls 22, 23, 24, 25, 26 and 27 which act upon it in the usual manner. The last pair 27 of these 20 rolls discharges the straw into a beater 28 which, it will be noted, runs in the opposite direction to that customary with similar devices. Beater 28 consists of a drum 29 along which are secured a number of longitudinal bars 30. This drum travels very rapidly, 25 acting upon the straw to separate a portion of the shives therefrom. The shives are discharged through a concave screen 31 and the remaining fiber through a mouth 32 formed in the beater casing 33 into a series 30 of rolls 34, 35, 36, 37 and 38, similar to the previously-mentioned break rolls. From the last pair of rolls 38 the straw passes into a second beater 39 similar to beater 28 and 35 from there into a kicker or shaker 46, best shown in Fig. 4. A shaking-shoe 40 having a perforated bottom 41 forms a portion of this device. Within the shoe 40 is positioned a plurality of forks 47 adapted to be 40 lowered and forwarded to feed the stock along the same in the usual manner. After the stock leaves said breaker the shives and other food products have been entirely removed from the fiber and the fiber is dis- 45 charged from said shaker to a horizontal belt conveyer 42. An inclined elevator 43 carries the fiber from belt 42 to a baling machine 44, after which the fiber may be disposed in any suitable manner.
50 It will be noted from Fig. 2 that the stock travels in a straight line from the time it enters hopper 15 to the time it is discharged on belt 42. Directly beneath all of the machines operating upon the stock during this 55 portion of the process is situated a long horizontal belt 45, the upper surface of which travels in the same direction as the stock in the machines. All of the screenings from the feeder 17, beaters 28 and 39, 60 and shaker 46, as well as all of the stock which drops through between the various rolls and other portions of the machines, is caught on the belt 45 and forwarded to an inclined elevator 48 which delivers it to an 65 inclined revolving perforated sifter drum

49. This drum serves to separate the shives and other food products from any fiber which may have been precipitated upon the belt 45. Any such fiber passes through the open end of the drum 49 into a spout 50 and 70 back on the belt 16, as previously mentioned, and is thence again passed through the de-cortinating process.

The shives and other screenings which are separated from the stock by drum 49 are 75 discharged from it through a hopper 51 and, as shown in Figs. 3 and 5, pass to a screenings separator 52 wherein they are properly dusted and cleaned. A belt conveyer 53 carries the shives and other food products 80 in the pure form to an inclined elevator 54 which delivers the same into an attrition mill 55, where the same is ground in a suitable manner to be used as stock food. An elevator 56 raises the ground shives to a small 85 bin 57. Bin 57 is provided with a feeding device 58 which conveys the ground shives at a uniform rate to an elevator 59. The shives are then discharged into a mixer 60, 90 where molasses from a reservoir 61 is delivered into it and mixed therewith. An inclined elevator 62 brings the finished stock-food product from the mixer 60 to a sacker 63, where the same is packed in the usual manner. Bin 57 serves merely as an overflow 95 reservoir for the grounds from which the same can be uniformly fed, as it would be impossible to vary the rate of flow of molasses in accordance with the flow of grounds from the mill. In this manner the shives 100 from the flax are directly formed into stock food from the flax straw in one continuous process, thus preventing infestation and loss of food value of the finished product.

The shive or cortex residue of the flax 105 straw which comes from the sifter drum 49 has been subjected to very violent beating and breaking operations in the course of its progress from the initial feeder to the sifter drum, during which time the fungus growth, 110 dust and other deleterious matter associated with the flax straw have been thoroughly disintegrated and loosened from the shive proper. All such matter is effectively and at once removed in the screening mill before 115 the shive has had opportunity again to become infected with the fungi and parasites which constitute the greater part of the dust and extraneous matter separated in the screening mill. This bright clean shive is 120 then immediately ground in the attrition mill 55 until it is reduced to a substance of the average consistency of meal. A good deal of finer material will be produced in the grinding which would render the food 125 difficult to feed directly to stock. Furthermore, the milling process cannot have completely removed the fungi and parasites which have been associated with the straw. It is, therefore, an essential feature of my 130

process immediately to treat the cleaned and powdered flax cortex with a substance which will serve to bind the powdered portions together and preserve the same by destroying and preventing growth of fungi and parasites. A most effective material for this purpose is crude molasses, which is itself an excellent stock food. The ground material is therefore immediately passed through the mixing device into which the molasses is fed. As a result of this mixing a roughly granular product is produced in which all powder is eliminated and wherein the particles of the ground shive or cortex are bound together in coarse granular form, the binder also serving as an effective preservative and a valuable stock food.

I claim:

1. The process of removing fiber from unretted flax straw and of preparing the residue for stock food which consists in subjecting the straw repeatedly and continuously to breaking and beating operations, collecting the material delivered from the breakers and beaters, sifting said material to remove fibers and unbroken portions therefrom, and immediately thereafter treating said sifted material with a preservative to render it available for stock food.
2. The process of removing fiber from unretted flax straw and of preparing the residue for stock food which consists in subjecting the straw repeatedly and continuously to breaking and beating operations, collecting the material delivered from the breakers and beaters, sifting said material to remove fibers and unbroken portions

therefrom, and immediately thereafter treating said sifted material with molasses to render it available for stock food.

3. The process of removing fiber from unretted flax straw and of preparing the residue for stock food which consists in subjecting the straw repeatedly and continuously to breaking and beating operations, collecting the material delivered from the breakers and beaters, sifting said material to remove fibers and unbroken portions therefrom, subjecting said sifted material to cleaning and grinding operations as the same is fed from the sifter, and treating the cleaned and ground material with a preservative binder for rendering the same available for stock food.

4. The process of removing fiber from unretted flax straw and of preparing the residue for stock food which consists in subjecting the straw repeatedly and continuously to breaking and beating operations, collecting the material delivered from the breakers and beaters, sifting said material to remove fibers and unbroken portions therefrom, subjecting said sifted material to cleaning and grinding operations as the same is fed from the sifter, and treating the cleaned and ground material with molasses for rendering the same available for stock food.

In testimony whereof I affix my signature in presence of two witnesses.

JONAS BROLIN.
